GAS ELIMINATOR

Robert M. Lindgren, Detroit, Mich., assignor to
Deep Wells, Inc., Detroit, Mich., a corporation
of Michigan

Application September 22, 1941, Serial No. 411,877

12 Claims. (Cl. 103—203)

My invention relates to a new and useful gas eliminator adapted for use primarily on oil wells.

In a very common type of oil well pump a tubular member is provided which is reciprocated and carries a valve known as a traveling valve. Below the traveling valve is a stationary valve and the construction of these parts is such, and these valves are so constructed and arranged, that when the tubular reciprocating member moves downwardly the traveling valve opens and allows the liquid beneath to flow upwardly and pass above the traveling valve. The standing valve remains closed and prevents the liquid from being forced downwardly. On the upward stroke the traveling valve moves into closed position so that the liquid above the same is lifted and the standing valve below moves into open position allowing liquid to flow into the chamber above the standing valve. Where gas is present frequently the space between the traveling valve and the standing valve becomes filled or partially filled with gas. When the tubular member is forced downwardly the traveling valve is held on the seat by the amount of liquid positioned above. When the space below is filled with liquid the pressure of the liquid is sufficient to lift the valve off its seat. However when the space below is filled with gas the traveling valve will not be lifted off its seat but the gas will be merely compressed, the standing valve preventing its escape downwardly. On the upward stroke the gas will again expand and thus the pump will be reciprocated to no purpose. When such a condition exists the pumping of liquid by the pump ceases and thus, what is commonly known as a gas lock has developed.

It is an object of the present invention to provide a pump structure so arranged as to eliminate and obviate such a situation and prevent the formation of a gas lock.

It is another object of the present invention to provide a structure whereby, upon the downward movement of the traveling valve a pre-determined distance, a liquid will be permitted to flow into the chamber between the traveling valve and the standing valve so as to force the gas out of the gas filled pump chamber.

It is another object of the present invention to provide, in a pumping mechanism having a pump chamber associated with a reciprocating part a member telescoping with the reciprocating part and so arranged and constructed that upon a pre-determined positioning of the reciprocating part and the telescoping part, liquid may

be permitted to flow from the exterior of these parts into the pump chamber.

It is another object of the present invention to provide in a pump structure of this type a means for eliminating or preventing the accumulation of a compressible fluid in the pump chamber.

Another object of the invention is the provision in a pumping mechanism of this type, of means whereby a compressible fluid entering the pump chamber may be displaced with a liquid.

In some types of oil wells, the well is placed under a vacuum for a period of time in order to draw the oil from surrounding territory into the basin of the well. In such cases when the pump becomes drained of all fluid the standing valve and traveling valve are locked in closed positions, the traveling valve being held in closed position by the fluid above, and the standing valve being held in closed position by a vacuum. It is an object of the present invention to provide a pumping mechanism so constructed and arranged that when operated to a predetermined position such a vacuum will be eliminated.

It is another object of the present invention to provide a pump structure, that, regardless of the pump space, will function efficiently and produce maximum volume of flow.

It is an object of the present invention to provide a pump structure having a reciprocating member and a member telescoping therewith and adapted for traveling in unison therewith and so constructed and arranged that said member will be hydraulically balanced when immersed in liquid.

Another object of the invention is the provision of a pumping mechanism having a reciprocating part and a part telescoping therewith and movable in unison therewith so arranged and constructed as to prevent said members becoming hydraulically locked in fixed relation when immersed in the liquid to be pumped.

Another object of the present invention is the provision of a pump structure so arranged, that it will lend itself to use with liners or without liners placed inside the working barrel thus making it possible to regulate the pump volume of flow, and therefore the overhead load, to the capacity range of the pump operating machinery.

Other objects will appear hereinafter.

It is recognized that various modifications or changes may be made in the detail of structure illustrated without departing from the spirit of the invention and it is intended that such variations and modifications shall be embraced within the scope of the claims forming a part hereof.

Forming a part of this specification are drawings in which,

In the structure illustrated in Fig. 1 and Fig. 2, I have indicated the pump and its working parts in the position which they would assume when the upward stroke is being made. In Fig. 5 and Fig. 6, I have illustrated the same pump structure with the working parts in the positions which they would assume when making the downward stroke and when gas has been encountered. If gas had not been encountered, the ball valve 64 in Fig. 5 would be in elevated position, permitting the liquid to flow through the opening in seat 63.

In the structure illustrated in Fig. 1 and Fig. 2, I have indicated an anchor shoe 35, having an inclined seat 36 formed thereon against which may seat, in sealing relation, the conical head 37 carried on the lower end of the pull tube 38. The upper end of this pull tube 38 carries a fitting 39 which has bore 41 formed therethrough in alignment with the bore 42 formed in the plunger 40 which is threaded at its lower end to the upper end of the fitting 39 and at its upper end to the valve cage 43. The upper end of the plunger 40 serves to press the valve-seat forming ring 44 into position on and secure it in position on the valve cage 43. A ball valve 45 is positioned in the cage 43 and adapted, when resting on the seat 44, to serve as a closure for the upper end of the plunger 40 and prevent downward flow of liquid through the plunger. It will be noted that this type of structure embodies a stationary plunger. Some pumps have a moveable plunger and a stationary barrel. The traveling valve used in these pumps is carried by the moveable part whether it is the pump barrel or the plunger. In the structure illustrated the ball valve 45 may be termed the standing valve.

The pump plunger 40 snugly engages as a slideable fit in the pump barrel 46 which carries the engagement nipple 47 at its lower end and which is connected at its upper end to one end of a fitting 48. Connected to the upper end of the fitting at its lower end is the tubular member 49 having its upper end increased in thickness as 54', and provided with the inclined bearing surface or engagement shoulder 54. Slidably engaging as snug fit in the tubular member 49, is a lifting tube 50 having the upper end reduced in outside diameter to provide the constricted portion 52 and thus form the engagement shoulder 53 adapted for engaging the inclined bearing or engagement surface 54. The bore through the tubing 49 is reduced in diameter by a thickened portion 54' to provide the constricted bore 55 in which the reduced portion 52 of the member 50 slidably engages in a snug fit.

The inner surface of the portion 54' is cut away, intermediate its ends, to provide the circumferential inner channel 57 which extends around the portion 52 and which communicates through the openings 58 with the interior of the tubing 34, and which is adapted to communicate with the openings 59 formed in the reduced tubular portion 52.

The upper end of the tubular portion 52 is provided with a lock nut 60 and threaded into one end of the fitting 62 and serves to press against and retain in position the annular seat-forming member 63 which serves as a seat for the ball valve 64. This valve is the traveling valve. Projecting upwardly from the cage 62 is the threaded stem 65 to which the sucker rod is attached.

In operation, through the reciprocation of the sucker rod, the member 61 and its attached parts may be reciprocated in the tubing 34 within predetermined limits of movement.

The structure illustrated in Fig. 1 shows the parts in their upward movement. When moving upwardly in the tubing 34 the valve 64 remains closed thus preventing liquid from entering the pump chambers from above, and the valve 45 is open to permit the flow of liquid upwardly into the pump chamber. Normally in operation on the downward stroke, the valve 45 would move into closed position and the valve 64 would open permitting the pump chamber to be cleared of

liquid. As the member 65 moves downwardly the pump barrel would remain stationary until the lock nut 60 contacts the member 54' at its upper end whereupon the pump barrel and the member 65 would move in unison with each other, the member 52 and the member 50 telescoping with the pump barrel 49 until the lock nut 60 engages the upper end of the portion 54'. On the upward movement these parts 49 and 50 would move relative to each other until the faces 53 and 54 engage.

For an efficient operation of these parts, however, it is necessary that the pump barrel be hydraulically balanced. Experience has shown that the difference in the liquid pressure at opposite ends of the pump barrel due to the length of the pump barrel is negligible and may be disregarded. If, of course, the pump barrel should be made of extraordinary length the difference in pressure would have to be taken into account. If the pressure on the upper end of the pump barrel 49 should be greater than the pressure on the lower end of the pump barrel the tendency would be to maintain the member 50 in the position shown in Fig. 1, so that the engaging faces 53 and 54 would always be in contact. On the other hand, if the pressure on the lower end of the pump barrel should be greater than the pressure on the upper end of the pump barrel, the pressure would have the tendency of maintaining the lock nut 60 and the member 54' in the position shown in Fig. 5.

Experience has shown that the cross section area, that is, the thickness of the pump barrel, must be maintained within certain limits due to a desire to reduce the weight as much as possible and obtain the desired bore. An examination of Fig. 1 will indicate that the lower end of the pump barrel 49 is of less thickness than the upper end or thickened portion 54'. This difference in thickness is accounted for by the formation of the shoulder and bearing face 54 and in this manner a true balance of the pump barrel 49 is obtained.

In operating, as the member 52 moves downwardly so as to telescope with the pump barrel 49, the openings 59 will move into registration with the openings 58. By having the inner surface of the member 54' cut away as at 57 to provide the internal channel, the openings 59 will be in communication with the openings 58 when registering with the channel 57, regardless of relative rotation of the member 52 and the pump barrel 49. When the downward stroke is being made, that is, when the lock nut 60 is in engagement with the end of the portion 54', the openings 59 will be in registration with the channel 57 thus establishing communication of the interior of the pump chamber or pump barrel 46 with the interior of the tubing 34. This will permit the liquid which is standing in the tubing 34 to flow inwardly and displace gas which may have accumulated in the pump chamber at any position above the standing valve. At the same time liquid may flow through the openings 56 formed in the member 49 and enter the chamber 66, thus establishing the hydraulic balance of the pump barrel and its connecting parts and preventing the forming of a vacuum in the chamber 46. It is, of course, obvious that the chamber 66 is sealed at its opposite ends by the engagement of the member 50 with the inner surface of the member 49 in sealing relation and by engagement of the member 50 in sealing relation with the inner surface of the member 54'.

The liquid entering the pump chamber through the openings 58 will thus establish a liquid pressure in the pump chamber equal to the liquid pressure in the tubing 34. As the pump barrel is moved downwardly the liquid therein will be subjected to additional pressure sufficient to lift the ball valve 64 off its seat and the liquid in the pump chamber will be permitted to escape through the valve seat 63 and through the openings 58 and 59, this liquid carrying with it any gas which may have accumulated in the pump barrel. The same action would effect a breaking of a vacuum which may have been established in the pump chamber through subjecting the well to vacuum "pull" over a period of time.

The engagement faces of the members 54' and 60 should previously be ground rough and in Fig. 9, I have indicated the engaging face of member 61', which functions as a stop member in the manner of the member 60, as provided with a groove. The purpose of having these engaging faces roughened is to prevent the parts becoming locked by virtue of the pressure which may surround them, whether it is air or liquid. In this way when the upward stroke begins from the position shown in Fig. 3 the parts 60 and 54' are readily disengaged.

In this manner I have provided a pump which is hydraulically balanced, and in which the formation of a gas lock or vacuum is prevented.

In Fig. 9 and Fig. 10, I have indicated a structure corresponding largely to the structure illustrated in Fig. 1 and Fig. 2. Corresponding parts are designated in Fig. 9 and Fig. 10 and the sections taken thereon with reference numerals corresponding to the similar parts in the structure illustrated in Fig. 1 and Fig. 2, the corresponding reference numerals in Fig. 9 and Fig. 10 being indicated as prime numbers.

The member 61' which corresponds to the member 61 of Fig. 1 serves as a contact member, the lock nut 60 being eliminated. This member 61' is provided on its face with the groove 60' for engaging the upper end of the member 54''' which corresponds to the member 54' of Fig. 1. The seat 54'' of Fig. 9 corresponds to the seat or engaging face 54 of Fig. 1.

Formed preferably integral with the member 61' is a tube 67 which functions as and corresponds to the tube 52 illustrated in Fig. 1. Mounted on the lower end of the tube 67 is an engagement ring 68 provided with an inclined engaging face 63' corresponding to the face 53 of Fig. 1. The end of the tube 67 is upset over the ring 68 as at 69 to retain this ring in position.

The member 47' corresponds to the member 47 of Fig. 2. This member threads into one end of a fitting 70. The opposite end of this fitting 70 threads into the lower end of the pump barrel 46'. Thus in the structure illustrated in Fig. 10 there is a departure from the structure illustrated in Fig. 2, accomplished by using the fitting 70. This is resorted to in order that the liner sections 71 may be easily and quickly inserted in position. These liner sections abut against one end of the fitting 48' and are engaged by one end of the fitting 70. The purpose of using the liners is to reduce the sucker rod load and provide a finer barrel finish. This reduction in the load is accomplished by reducing the volume capacity of the pump. It will be noted that the openings 56 shown in Fig. 1 are not present in the structure shown in Fig. 9. Otherwise the structure illustrated in Fig. 9 and Fig. 10 is similar to the structure illustrated in Fig. 1 and Fig.

2 and the various features and functions and results of the structure illustrated in Fig. 1 and Fig. 2 are present in the structure illustrated in Fig. 9 and Fig. 10.

In Fig. 13, I have illustrated a fragment of a pump in which the structure is slightly modified from that already described. The valve cage 72 is provided with a threaded stem 73 for attachment to the sucker rod. Positioned in the valve cage 72 is the ball valve 74 fitting on the seat-forming ring 75 which is held in position by one end of the fitting 76. Threaded into the opposite end of the fitting 76 is the pipe 77 carrying the lock nut 78. Slidably mounted on the pipe 77 is the barrel 81 carrying the top portion 79. This barrel and this top portion 79 will be free to rotate on the pipe 77 or may be secured against rotation while at the same time permitting longitudinal relative movement. Formed in the tube 79 are openings 80 which correspond to the openings 59 of Fig. 1. The lower end of the tube 77 is formed into a piston, cut away as at 83 to provide a clearance or channel communicating with the vent openings 86. This portion is also provided with grooves 84 in which may be positioned packing or sealing rings 85. This structure is illustrated and may be resorted to when it is desired to compensate for mis-alignment of the parts 79 and 87 when threaded together. When this structure is resorted to, a finely machined fit between engaging surfaces of the member 77 and the pump barrel 81 is not required as the expanding packing or sealing rings 85 would compensate for any roughness in machining which might be present.

In Fig. 18 and Fig. 19, I have illustrated a modification of the invention and in these views I have illustrated an anchor shoe 88 having an inclined seating surface 89 against which engages the conical surface 91 of the head 90 which is connected at its upper end to the valve cage 93 having the inwardly projecting shoulder 94 against which the seat-forming ring 95 is held by the end of the head 90. A ball valve 96 is positioned in the cage 93. A pin 98 is extended diametrically through the cage 93. A nipple 97 on the upper end of cage 93 threads into one end of a coupling 99, the other end of which threads into the lower end of the pump barrel 101. Thus the pump barrel is mounted stationary. Liner sections 102 are mounted within the barrel 101. Threaded into the upper end of the barrel 101 is one end of a fitting 103 which engages one of the end sections of the liner 102, the other end section engaging an end of the coupling 99. Positioned in the fitting 103 is a guide ring 104 which projects through the head 105 threaded into the upper end of the fitting 103. This head 105 is provided with lateral openings 106 and the ring 104 is provided with axial openings 107. Slidably projected through the head 105 and the guide ring 104 is a rod 108 which connects to the upper end of valve cage 109 in which is positioned the ball valve 110 adapted to rest upon the seat-forming ring 111. This ring is engaged by one end of the connector 112 which is threaded into the lower end of the valve cage 109 and which also threads onto the plunger extension tube 113. A lock nut 114 is threaded onto the tube 113. Embracing the tube 113 and slidably relatively thereto, within predetermined limits, and slidable in unison therewith is a sleeve 115. Laterally directed openings 116 are formed in the tube 113 and adapted, when the lock nut 114 engages the upper end of the sleeve 115, for registering with the

openings 117 formed in the sleeve 115 and for communicating with the peripheral channel 118 extending around the tube 113. An axially directed passage 119 communicates at one end with the groove or channel 118 and at its opposite end with the groove or channel 118 shown in Fig. 19. The tube 113 may be termed the plunger tube inasmuch as it is formed at its lower end with the piston-like plunger 120 having the peripheral grooves 121 formed therein for receiving sealing or packing rings. The meeting faces of members 114 and 115 are finished rough so that an atmospheric or hydraulic locking of these faces together is prevented.

15 In operation, the rod 108, to which is connected the sucker line, is reciprocated so as to reciprocate the plunger in the stationary pump barrel 101 which is positioned in spaced relation to the tubing 34" to which the anchor shoe 88 is connected. 20 As the rod 108 moves downwardly the lock nut 114, through engagement with the upper end of the sleeve 115, will force this sleeve to travel in unison with the tube 113 after the openings 116 have been brought into registration with the channel or groove 118. When this registration is 25 effected the gas lock or vacuum, herein previously referred to, will be eliminated and the sleeve 115 will be in hydraulic balance, the liquid being permitted access to the lower end of the sleeve 115 through the passage 119. As the plunger is forced downwardly the liquid will be forced upwardly through the bore of the plunger and through the plunger tube 113 forcing the valve 110 off its seat, the liquid traveling upwardly and having access to the well tubing 34" through the opening 106. In this movement the ball valve 96 will be resting upon its seat. In the reverse movement the ball 96 will be lifted from its seat. The sleeve 115 and the tube 113 will be 30 moved to the relative positions shown in Fig. 18, and the ball valve 110 will rest upon its seat.

35 It is obvious that a prevention of a gas lock in a well of this type is accomplished in substantially the same manner as previously described 40 for the other forms. Anyone skilled in the art will understand that the pump barrel may be anchored either above or below.

In Fig. 25, I have indicated a structure in which the ball valve 74, illustrated in Fig. 13, is eliminated, and the upper end of the fitting 76 corresponding to the fitting 76 of Fig. 13 is closed by a disc 160 mounted within the cage 161 from which extends the threaded nipple 162 for attachment to the sucker rod. In such a structure the liquid 55 pumped would have access to the well tubing through the openings 84 illustrated in Fig. 13. Experience has shown that this structure is operative so that the traveling valve may thus be eliminated when desired. This structure is particularly adapted where the pumping mechanism 60 is operated at slow speed.

It is obvious that in all of the structures illustrated, the parts may be easily and quickly assembled and disassembled. Another feature 65 which is obvious is the compactness and lightness of the device. The structures also are such as to lend themselves to a production method of manufacture.

In operation the pump would ordinarily be 70 immersed in liquid. This is true whether the pump ordinarily is positioned immersed in the liquid or is positioned well above the liquid to be pumped.

When positioned well above the liquid to be 75 pumped, the liquid will be discharged from the

upper end of the pump and gradually fill the well tubing to a level which is above the pump. Ordinarily a gas lock would not develop in a pump until the column of liquid above the pump exerted pressure on the traveling valve sufficient to counter-balance the compression of the gas within the pump chamber.

It will be noted that the breaking of the gas lock briefly consists in bleeding a liquid from around the pump into the interior or into the pump chamber between the traveling valve and standing valve which may be termed the end valves of the pump. This bleeding is accomplished on the out-put stroke of the pump and the bleeding ports are closed on the in-take stroke of the pump.

What I claim as new is:

1. In a pump mechanism of the class described, adapted for operation while immersed in liquid, a pump barrel having a liquid receiving chamber therein; a tubular plunger, said plunger and said barrel being associated in telescopic relation and slidably longitudinally of each other; a valve mechanism at each end of said chamber for opening and closing the same, said valves being arranged so that one valve is open when the other is closed and vice versa; and means for bleeding a liquid into said chamber between said valve mechanisms through said plunger.

2. In a pump mechanism of the class described, adapted for operation while immersed in liquid, a pump barrel having a liquid receiving chamber therein; a tubular plunger, said plunger and said barrel being slidably longitudinally of each other; a valve mechanism at each end of said chamber for opening and closing the same, said valves being arranged so that one valve is open when the other is closed and vice versa; and means for bleeding a liquid into said chamber through said plunger between said valve mechanisms during movement of the barrel in one direction and preventing bleeding during movement of the barrel in the opposite direction.

3. In a pump mechanism of the class described, adapted for operation while immersed in liquid, a pump barrel; a tubular plunger in telescoping relation with said barrel; a valve in said tubular plunger; a tubular extension on said barrel; lateral openings in said extension; a tubular member telescoping said barrel extension; lateral openings in said last-named tubular member and communicable with the lateral openings in said extension; and a valve at the end of said last-named tubular member, said valve being adapted to remain open when said first-named valve is closed and vice versa.

4. A pumping mechanism embodying a pair of telescoping reciprocable tubular parts; one of said parts constituting a pump barrel and the other constituting a plunger; an oil conduit in said parts; valve means for closing the ends of said tubular parts; a tubular extension on one of said tubular parts; a tubular member telescoping said tubular extension and reciprocable with respect thereto; a valve for closing one end of said last-named tubular member; and lateral openings in said last-named tubular member and said tubular extension arranged to communicate with said oil conduit.

5. In a pump mechanism of the class described, adapted for operation while immersed in liquid; a tubular plunger, a valve on said plunger for closing the same; a second tubular

member; a valve for closing one end of said last-named member, said tubular members being arranged in telescopic relation at one of their ends, and adapted for slidable longitudinal relative movement, the interior of one tubular member communicating with the interior of the other; means for bleeding liquid into the interior of said members upon telescopic movement of said members in one direction to a predetermined position; and means for limiting the relative longitudinal movement of said members.

6. In a pump mechanism of the class described, adapted for operation while immersed in liquid, a pair of tubular sections, said sections being arranged at one of their ends in telescopic relation, slidable longitudinally of each other, one of said sections comprising a pump barrel and the other of said sections comprising a plunger; a pair of valves, there being a valve at one end of each of said sections for closing the same, the first section having lateral openings formed therethrough in communication with the liquid in which it is immersed; a third tubular section slidably engaged in said first section and having lateral openings formed therethrough and communicable with the opening of the first section, said lateral openings being adapted for communication with the openings in said first section upon movement of said third section to a predetermined position relative to said first section.

7. In a pump mechanism of the class described, adapted for operation while immersed in liquid, a pair of tubular sections constituting an upper section and a lower section, said sections being arranged at one of their ends in telescopic relation and slidable longitudinally of each other; a plunger in said lower section; a pair of valves, there being a valve at one end of each of said sections for closing the same, one of said sections having lateral openings formed therethrough in communication with the liquid in which it is immersed; lateral openings in said other section being adapted for communication with the openings in said first section upon movement of either section to a predetermined position relative to said other section; and means carried by one section for engaging said other section upon alignment of said openings thereby forcing said other section to travel in unison with said first section.

8. In a pump mechanism of the class described, adapted for operation while immersed in liquid, a pair of tubular sections, said sections being arranged at one of their ends in telescopic relation slidable longitudinally of each other; a plunger in one section; a pair of valves, there being a valve at one end of each said sections for closing the same, one of said sections having lateral openings formed therethrough in communication with the liquid in which it is immersed; lateral openings in said other section being adapted for communication with the openings in said first section upon movement of said second section; means carried by said second section for engaging said first section upon alignment of said openings and thereby forcing said first section to travel in unison with said second section and means for moving said sections in unison upon movement of said first section in the opposite direction out of opening aligning position a predetermined distance.

9. In a pump of the class described, adapted for operation while immersed in liquid, a pair of tubular sections arranged at one of their ends in telescopic longitudinally slidable relation, one of

said sections forming a pump chamber and the other of said sections forming a tubular plunger communicating with said chamber; valves for closing the ends of said sections; means for anchoring one of said sections stationary; a reciprocating mechanism; a floating connection between said reciprocating mechanism and the other of said sections; alignable ports in said reciprocating mechanism and said floating connection, said floating connection being arranged for moving one of said sections in unison with said reciprocating mechanism in either direction, subsequent to the movement of said reciprocating mechanism a predetermined distance in either direction; and means for maintaining the reciprocated section in hydraulic balance in the liquid in which it is immersed.

10. In a pump structure of the class described, adapted for operation while immersed in liquid, a pair of tubular sections arranged at one of their ends in telescopic longitudinally slidable relation, one of said sections providing a pump barrel and the other of said sections providing a plunger; a traveling valve on the upper end of said barrel structure for preventing return flow of liquid into said barrel; a valve on the lower end of said barrel structure for preventing return flow of liquid from said barrel, said barrel section having, between said valves, openings for communicating the interior thereof with the liquid in which it is immersed; a third section telescoping said first section and having means formed therein for registering with the openings in said first section upon movement of said third section to a predetermined position and means for closing communication of the interior of said first and third sections with the liquid in which it is immersed.

11. In a pump structure of the class described, adapted for operation while immersed in liquid, a pair of tubular sections arranged at one of their ends in telescopic longitudinally slidable relation to provide a chamber; a traveling valve at the upper end of one of said sections for prevent-

- ing return flow of liquid into said chamber; a valve at the lower end of the other section for preventing return flow of liquid from said chamber, one of said sections having, between said valves, openings for communicating the interior thereof with the liquid in which it is immersed; one of said sections telescoping the other and longitudinally movable relatively thereof and having openings formed therein for registering with said openings in said chamber upon movement of said sections to a predetermined position; means for moving said sections out of said predetermined position and for closing communication of the interior of said chamber with the liquid in which it is immersed; and means for maintaining said tubular member in hydrostatic balance in said liquid and preventing vacuum lock between the said sections and said tubular member.
12. In a pump structure of the class described, adapted for operation while immersed in liquid, a pair of tubular sections arranged in telescoping longitudinally slidable relation; one of said sections providing a tubular plunger and the other of said sections providing a pump barrel; a valve for preventing return flow of liquid into said barrel from one end; a valve for preventing return flow of liquid from said barrel at its opposite end, said barrel sections having lateral openings formed therethrough between said valves for communicating said barrel with the liquid in which it is immersed; a tubular member telescoping and longitudinally slidable in said barrel section and having openings adapted for registering with the openings in said barrel section upon movement of said section to a predetermined position relative to said tubular member; interengaging means between said last-named member and said barrel section for effecting a movement of the same in unison with each other upon the registration of said openings; and means for disengaging said interengaging parts.

ROBERT M. LINDGREN.
